UNITED STATES PATENT OFFICE

ADOLPH F. HERZIG, OF EAST ST. LOUIS, ILLINOIS.

ORE-ROASTING FURNACE.

1,108,906.

Specification of Letters Patent.

Patented Sept. 1, 1914.

Application filed August 12, 1913. Serial No. 724,502.

To all whom it may concern:

Be it known that I, ADOLPH F. HERZIG, a citizen of the United States of America, residing at the city of East St. Louis, State of Illinois, have invented a certain new and useful Ore-Roasting Furnace, of which the following is such a full, clear, and exact description as will enable any one skilled in the art to which it appertains to make and use the same, reference being had to the accompanying drawings, forming part of this specification.

My invention relates to an ore roasting furnace of the type described in Letters-Patent of the United States, No. 303,571, granted to E. C. Hegeler August 12, 1884, and more particularly to the mechanism for moving the rakes longitudinally through the roasting chambers of such furnace.

In all of the actuating mechanisms used in connection with such furnaces heretofore, in so far as I am aware, the friction or sprocket wheels for moving the rakes have been mounted on horizontally arranged shafts. This not only causes difficulty in securing room for the wheels when the roasting chambers are close together, but also requires a large amount of bevel gearing for driving the wheels.

One of the main objects of my invention is to simplify the operating mechanism and reduce the amount of gearing required, and this I accomplish primarily by mounting the sprocket wheels for driving the rakes on vertically arranged shafts.

In the accompanying drawings, which illustrate one form of ore roasting furnace made in accordance with my invention, Figure 1 is a top plan view on a reduced scale; Fig. 2 is a vertical section; Fig. 3 is an enlarged sectional view showing one of the rakes; Fig. 4 is an enlarged end view of the operating mechanism; Fig. 5 is an enlarged section taken on the line 5—5 of Fig. 4; and Fig. 6 is a side elevation of the part shown in Fig. 4.

Like marks of reference refer to similar parts in the several views of the drawings.

10 represents the roasting furnace which 50 comprises a double series of roasting chambers 11 arranged side by side as shown in Figs. 1 and 2. Adjacent to each end of the furnace 10 is a set of rotary tables 12. These 55 tables are arranged on shafts 13 so that they may be moved into position to coöperate first

with one series of roasting chambers and next with the other series. Arranged upon the tables 12 are the rakes 14 shown in detail in Fig. 3. Each of the rakes 14 is provided with a number of cutter bars 15 and is adapted to be engaged by a rod 16 passing through one of the roasting chambers 11 and secured to the actuating mechanism, as will be hereinafter more fully described. Adjacent to each side of tables 12 are a pair of vertical shafts 17 carrying idlers 18, around which pass sprocket chains 19. The size and arrangement of the idlers 18 is such that the outer sides of the sprocket chains 19 are in alinement with the central portion of the two sides of roasting chambers 11. The sprocket chains 19 also pass around sprocket wheels 20, loosely mounted on vertical shafts 21. These vertical shafts 21 are mounted in a framework 22 and have secured to their ends a pair of meshing spur wheels 23. One of these wheels 23 is engaged by a pinion 24, as shown in Fig. 5. This pinion 24 is mounted on the upper end of a shaft 25, the lower part of which carries a large bevel gear 26, meshing with a small bevel gear 27 mounted on shaft 28. On the end of shaft 28 is a pulley 29 driven by a belt 30 from an electrical motor 31, or other suitable source of power which may be reversed. Each of the sprocket wheels 20 is adapted to be operatively connected with the shaft 21 by means of a clutch 32, preferably of the dog type. The movable part of the clutch 32 is engaged by means of an arm 33 carried on a rock shaft 34 mounted in the framework 22. The outer end of each of the shafts 34 has secured to it a double lever 35, as best shown in Fig. 6. Secured to the inner end of each of the levers 35 is a coil spring 37 which normally holds the inner end of the said lever upwardly, thus holding the clutch out of operative position so that the shafts 21 may rotate without actuating the sprocket wheels 20. The inner end of each of the arms 35 also has attached to it a cable 38 and the outer end has attached to it a similar cable 39. These cables 38 and 39 pass outwardly and extend around pulleys 40 and 41 respectively. The cables 38 and 39 after passing around the pulleys 40 and 41 extend to a position adjacent to the furnace 10 where they are actuated by suitable levers 42, as shown in Fig. 2.

The operation of my device will be readily

understood. After the furnace has started, the rod 16 is attached at one end to the upper sprocket chain 19 and at the other to one of the rakes 12, as shown in Figs. 1 and 2 of the drawings. The proper lever 42 is now operated to cause the upper clutch 32 to connect its sprocket wheel 20 to the shaft so that the sprocket wheel will be rotated, thus drawing the rake through the upper chamber. This process is repeated with the lower rakes until the material has been fed through the entire set of roasting chambers at one side, after which the tables 12 are rotated and a like process repeated on the other side. It will be apparent that I secure the desired result with the least possible amount of gearing and, at the same time, the disposition of the sprocket wheels 20 is such that they may be properly placed whether the roasting chambers 11 are close together or far apart. The springs 37 hold the clutches 32 out of engagement with their sprocket wheels so that the sprocket wheels will not become accidentally engaged with the shafts and these springs also assist in disengaging the stationary and movable springs of the clutch.

Having fully described my invention, what I claim as new and desire to secure by Letters Patent of the United States is:

1. The combination with an ore furnace divided into a plurality of compartments, of a shaft having a plurality of wheels mounted thereon, means for independently connecting each of said wheels to said shaft, raking mechanism coöperating with different compartments of the furnace and driven

by said wheels, and means for driving said shaft.

2. The combination with an ore furnace 40 divided into compartments, of a shaft having a plurality of wheels mounted thereon, means for independently connecting each of said wheels operatively to said shaft, a second shaft carrying idlers and arranged between said first named shaft and said furnace, raking mechanism coöperating with different compartments of the furnace and driven by said wheels, and means for driving said first named shaft.

3. The combination with an ore roasting furnace divided into a plurality of compartments, of a pair of vertical shafts, gearing driving said shafts in opposite directions, sprocket wheels arranged on said shafts, 55 idlers, sprocket chains passing around said sprocket wheels and idlers, raking mechanism coöperating with the different compartments and driven from said sprocket chains, clutches for throwing said sprocket 60 wheels into engagement with said shafts, rock shafts operating said clutches, means normally holding said rock shafts in position to release said clutches, and connections actuating said rock shafts to apply the 65 clutches.

In testimony whereof, I have hereunto set my hand and affixed my seal in the presence of the two subscribing witnesses.

ADOLPH F. HERZIG.

Witnesses:

W. A. ALEXANDER,
G. M. SHORE.
